UNITED STATES PATENT OFFICE

2,573,760

MECHANICAL COMPASS PENCIL

Lloyd G. Cherne, Minneapolis, Minn.

Continuation of application Serial No. 743,934,
 April 25, 1947. This application April 8, 1949,
 Serial No. 86,317

4 Claims. (Cl. 33—27)

1

This application is a continuation of application Serial No. 743,934, filed April 25, 1947, which is now abandoned, and relates to an invention on a mechanical pencil and compass, and having as its primary object the provision of an article which may be utilized as a conventional mechanical pencil, or alternatively, as a compass, as desired.

A further object of the invention is the provision of a device of this character wherein the compass leg is adapted to lie substantially flush with the pencil body when not in use, thus avoiding interference with the device when used as a pencil.

A further object of the invention is the provision of a compass leg in association with a mechanical pencil, adapted to be extended therefrom, whereby the device may be used as a compass, the leg being extensible, as desired.

Still another object of the invention is the provision of such a device provided with means, whereby the same may be used as dividers, when desired.

Still other objects reside in the combinations of elements, arrangements of parts, and features of construction, all as will be more fully pointed out hereinafter and disclosed in the accompanying drawing, wherein there is shown a preferred embodiment of this inventive concept.

In the drawing:

Figure 1 is a side elevational view of one form of device embodying features of the instant invention, certain concealed portions thereof being indicated in dotted lines;

Figure 2 is a longitudinal sectional view taken substantially through the center line of the device shown in Figure 1, with the cap removed;

Figure 3 is a view taken in side elevation, disclosing the compass leg extended, and the cap removed from the pencil;

Figure 4 is a sectional perspective view showing the means for extending the compass leg;

Figure 5 is a sectional view taken substantially along the line 5—5 of Figure 2, as viewed in the direction indicated by the arrows;

Figure 6 is a sectional view taken substantially along the line 6—6 of Figure 4, as viewed in the direction indicated by the arrows;

Figure 7 is a sectional view taken substantially along the line 7—7 of Figure 2, as viewed in the direction indicated by the arrows.

Similar reference characters refer to similar parts throughout the several views of the drawing.

Referring now to the drawing, the device of

2

the instant invention includes a body portion 10 and a separate tip portion 11. The body portion contains a lead reservoir 12, open at its upper end and adapted to contain extra leads, and has 15 extending inwardly thereto a helix 13 including a groove or channel 14 adapted for guidance of a projection 15 movable in a slot in a tube 16 carried interiorly of the helix. The projection 15 is secured to a lead-feeding, rod-like member 18, while the end of the tube 16 is secured to a collar 19, secured to the rotatable tip 11. The arrangement is such that rotation of the tip 11 relative to the body portion 10 will cause movement of the projection 15 and correspondingly of the rod 18, to feed lead downwardly to the point. The arrangement heretofore described is largely conventional, and its sole pertinence to the instant invention resides in the provision of a relatively sharp point 20 (see Figure 20) on the lead-feeding rod 18, whereby the point may be extruded from the tip 11 of the pencil in such manner as to be used, when the lead is removed from the barrel, as a divider point.

The body 10 has at its upper extremity an extending portion 25 of reduced diameter, open at its extremity, in which open extremity is adapted to be seated an eraser-holding cup 26, provided with an eraser 27, and including a portion 28 of reduced diameter adapted to fit within the open end of the portion 25. Adjacent its outer extremity, the portion 25 has pivotally secured thereto, as by means of a pivot 29, the upper extremity of a compass leg 30, a groove or channel 31 being provided in the body portion for the accommodation of leg 30 in such manner that when the parts are in nested or folded relation, as shown in Figure 2, the portion 30 is substantially flush with the outer wall of portion 25. Adjacent the juncture of portion 25 with body 10, the leg 30 is provided with an offset extending portion 30', a fingernail notch 32 being provided, and extends as a section, generally indicated at 33, into a channel 34 in the side of the body 10 in such manner that this portion also lies flush with the pencil when not in use. A cap portion 35 having a clip 36 thereon is adapted to be positioned on extending portion 25 when the compass leg is closed, for the purpose of holding the leg closed, and in flush relation to the body of the pencil.

A clamping means or two oppositely-disposed clamping fingers 40 of a U-shaped member, Figure 7, are positioned on opposite sides of the pivoted extremity of compass leg 30 and extend upwardly into the interior of portion 28 of member

26, the fingers 40 being connected to the pivot 29. As best shown in Figure 5, the interior of portion 28 is provided with two oppositely-disposed cam surfaces 41, the arrangement being such that when the eraser cup 26 is rotated in a clockwise direction, the cam surfaces 41 will act to clamp the fingers 40 on opposite sides of leg 30 substantially to preclude movement thereof. Conversely, counter-clockwise rotation of the device will release the engagement of the clamping fingers 40 and permit the compass leg 30 and its associated parts to be moved, as desired.

Means are provided for extending the compass leg to a length substantially equal to that of the pencil body 10 and its associated tip 11, and take the form, as best shown in Figure 4, of a separable section 44 comprising a part of the extension 33, provided with side guide rods 45 engageable in suitable channels 46 formed in the portion 47 of extension 33, which is integral with the leg portion 30. The end of portion 47 is, as best shown in Figures 4 and 6, provided with a rectangular aperture 48 adapted to be engaged by teeth 49 on the upper portion of a locking bar 50, the opposite end of which is secured to a spring member 51, which is, in turn, secured to portion 44. The arrangement is such that when the parts are extended to the positions shown in Figure 4, teeth 49 engage with the upper portion of the aperture 48 in such manner as to hold the parts in extended relation to preclude slippage thereof. Downward pressure on the member 50 will release the engagement and permit the device to be retracted, the members 45 sliding in their associated guide channels 46.

The portion 44 is provided with a relatively sharp point 52.

From the foregoing, it will now be seen that there is herein provided a device which may be readily utilized as a mechanical pencil, as a compass, or as dividers, as desired, the compass leg being provided with means whereby the same may be extended or retracted to the desired length, and locking means being provided to hold the compass leg in any desired position of adjustment, which accomplishes all of the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

What is claimed is:

1. In a mechanical pencil having a body portion having one end open, a rotatable cup for closing the open end of said body portion, clamping means supported in said cup, a compass leg having one end pivotally connected to said clamping means and said body portion for movement into and out of nested relationship with respect to the body portion, and means on the inner face of said cup frictionally engageable with said clamping means upon rotation of said cup in one direction to thereby preclude movement of said pivoted end of said leg and disengageable from said clamping means upon rotation of said cup in the opposite direction to thereby permit movement of said pivoted end of said leg.

2. In a mechanical pencil including a body portion having one end open, a rotatable cup for closing the open end of said body portion, clamping means supported in said cup, a compass leg having one end pivotally connected to said clamping means and said body portion for movement into and out of nested relationship with respect to the body portion, and means embodying opposed cam surfaces on the inner face of said cup frictionally engageable with said clamping means upon rotation of said cup in one direction to thereby preclude movement of said pivoted end of said leg and disengageable from said clamping means upon rotation of said cup in the opposite direction to thereby permit movement of said pivoted end of said leg.

3. In a mechanical pencil including a body portion having one end open, a rotatable cup for closing the open end of said body portion, opposed clamping fingers supported in said cup, a compass leg having one end pivotally connected to said clamping fingers and said body portion for movement into and out of nested relationship with respect to the body portion, and means embodying opposed cam surfaces on the inner face of said cup frictionally engageable with the opposed clamping fingers upon rotation of said cup in one direction to thereby preclude movement of said pivoted end of said leg and disengageable from the opposed clamping fingers upon rotation of said cup in the opposite direction to thereby permit movement of said pivoted end of said leg.

4. In a mechanical pencil including a body portion having one end open, a rotatable cup for closing the open end of said body portion, clamping means supported in said cup, a compass leg having one end pivotally connected to said clamping means and said body portion for movement into and out of nested relationship with respect to the body portion, means embodying opposed cam surfaces on the inner face of said cup frictionally engageable with said clamping means upon rotation of said cup in one direction to thereby preclude movement of said pivoted end of said leg and disengageable from said clamping means upon rotation of said cup in the opposite direction to thereby permit movement of said pivoted end of said leg, and a cap adapted to be positioned over the end of said body portion closed by said rotatable cup when said compass leg is in nested relationship with respect to said body portion for holding said compass leg in such nested relationship.
